US00D481017S

(12) United States Design Patent **(10) Patent No.:** **US D481,017 S**
Hsia et al. **(45) Date of Patent:** **** Oct. 21, 2003**

(54) HEAT SINK

(75) Inventors: **Chih-Hao Hsia**, Banqiao (TW);
Kuo-Cheng Lin, Taoyuan (TW);
Wen-Shi Huang, Taoyuan (TW)

(73) Assignee: **Delta Electronics Inc.**, Taoyuan Hsien (TW)

(**) Term: **14 Years**

(21) Appl. No.: **29/171,546**

(22) Filed: **Nov. 25, 2002**

(30) Foreign Application Priority Data

Sep. 13, 2002 (TW) 91305155

(51) LOC (7) Cl. **13-03**

(52) U.S. Cl. **D13/179**

(58) Field of Search D13/179; 174/16.3, 174/52.4; 165/80.3, 104.14, 104.33, 121, 122, 180, 185; 206/713, 714, 715, 716, 727, 728; 257/706, 707, 718, 719, 720, 721, 722, 727, 686; 361/271, 274.3, 697, 702, 704, 709, 710, 711
